United States Patent Office

Des. 176,108
Patented Nov. 22, 1955

176,108

CHEEK PAD

Gordon Dayton, Portland, Oreg.

Application August 20, 1953, Serial No. 26,526

Term of patent 14 years

(Cl. D30—1)

Fig. 1

Fig. 2

Fig. 3

Figure 1 is a rear perspective view of a cheek pad, showing my new design.

Figure 2 is a face view of the cheek pad.

Figure 3 is an end view thereof, looking in from the left of Figure 2.

I claim:

The ornamental design for a cheek pad, as shown.
